UNITED STATES PATENT OFFICE.

WILLIAM C. FLANNERY, OF WASHINGTON, DISTRICT OF COLUMBIA.

FASTENER FOR CONCRETE SEWER CONSTRUCTIONS.

1,155,411.

Specification of Letters Patent.

Patented Oct. 5, 1915.

Application filed September 3, 1913. Serial No. 788,017.

To all whom it may concern:

Be it known that I, WILLIAM C. FLANNERY, a citizen of the United States, residing at Washington, District of Columbia, 5 have invented certain new and useful Improvements in Fasteners for Concrete Sewer Constructions, of which the following is a specification.

This invention relates to fasteners for concrete sewer constructions, and particularly to fasteners for use in connecting and holding assembled the inner wall forming elements of a sewer preparatory and subsequent to the operation of embedding the 10 same in an outer inclosing wall of concrete, the invention being especially directed to sewers of the type shown in my prior applications #639,454, filed July 19, 1911, and #683,317, filed March 12, 1912, wherein the 15 sewer or other conduit is composed of a frame structure including rings or bands, an inner wall, lining or shell of tiles, an outer wall of concrete, and means for supporting the shell at an elevation above the bed of 20 the sewer in order that the concrete may be 25 filled in.

The object of the present invention is to provide a fastener whereby tiles composing the inner wall may be fastened to the supporting means and to the frame rings or bands and also to each other in a ready and secure manner, so as to hold the elements assembled while the concrete is being filled in, and to coöperate therewith to form an 30 embedded framing and reinforcement for the inner wall of maximum strength and durability.

A further object of the invention is to provide a type of fastener which may also 40 be employed for reinforcing and holding a starting tile and frame ring connected firmly with a supporting block or pedestal, and for holding all the other tiles in spaced relation to the frame rings, so that the concrete will 45 embed all portions of the structure in a substantially monolithic manner.

The invention consists of the features of construction, combination and arrangement of parts, hereinafter fully described and 50 claimed, reference being had to the accompanying drawing, in which:—

Figure 1 is a perspective view of my improved fastener; Fig. 2 is a vertical longitudinal section on the line 2—2 of Fig. 4, 55 showing a fastener arranged to couple ad-

jacent tiles and connect the same with a frame ring; Fig. 3 is a view in end elevation of the parts shown in Fig. 2; Fig. 4 is a vertical transverse section through a completed sewer, taken on a line coincident 60 with one of the frame rings or bands and showing the application of the invention; Fig. 5 is a perspective view, showing the mode of fastening adjoining tiles together; Fig. 6 is a perspective view of a modified 65 form of fastener.

In carrying my invention into practice I provide a fastener 1, formed of stout spring wire, said fastener comprising a U-shaped body portion formed of parallel side arms 2 70 united at one end by a transverse connecting member 3. From the free ends of the arms 2, the portions of the wire are bent inwardly at an angle on converging lines toward the cross piece 3 and between the arms 2 to provide portions 4, thence bent outwardly at right angles or perpendicularly to the plane of the portions 2, 3 and 4 to provide connecting members 5, and finally bent at their extremities to produce hooks or engaging 75 members 6, lying in the same transverse plane which is parallel to the transverse plane of the arms 2. The arms 2 of the body portion are relatively movable and provide spring clamping or engaging members, and the free ends of said arms also coöperate with the portions 4 to provide engaging members, and the hooks 6 further serve as engaging members, as hereinafter 80 fully described.

In the illustrated mode of application and use of the invention, I have shown a sewer or like conduit composed of base or starting tiles 7 supported by concrete pedestals 8, as shown in Fig. 4, frame rings or bands 9, 95 tiles 10 similar in construction to the tiles 7 and coöoperating therewith to form the inner wall or lining of the sewer, fasteners of the construction described whereby the parts are initially held assembled, and an outer concrete wall 11, in which the aforesaid component parts of the sewer to be concreted are embedded. Each of the aforesaid tiles is segmentally curved in a transverse direction and provided in its outer or rear surface 100 with a dove-tailed groove 12 having undercut side walls 13, the said grooves 12 opening through the opposite ends of the tiles.

The body portion of each fastener is adapted to be inserted in the groove 12 of a 110

tile, and the corresponding grooves of adjoining tiles, so that the arms 2 underlie and interlock with the dove-tailed side walls 13. A fastener of the character set forth is positioned in the groove midway the length of each starting tile 7 with the portions 5 and 6 projecting therefrom and embedded in the concrete pedestal 8, the concrete of the pedestal also filling the groove in the tile and locking the parts together. The hooks 6 are adapted to engage the frame rings or bands 9, and the base portion of each frame ring or band extends through and is embedded in its supporting pedestal 8 and is engaged by the hooks of the fastener held in the central portion of the starting tile 7, whereby the pedestal, starting tile and frame ring or band are all rigidly united.

In the construction of the sewer a continuous series of the pedestals and starting tiles and frame rings supported thereby are arranged in proper spaced relation along the bed of the sewer trench, the ends of adjacent starting tiles united by fasteners of the described type, the remaining tiles 10 then assembled and fastened to each other and to the frame rings or bands by other fasteners, thus producing a skeleton frame work and inner wall, lining or shell, after which the concrete forming the outer wall 11 is filled in, and embeds and ties the afore-mentioned parts homogeneously together.

In uniting the adjacent ends of starting tiles, one end or the other of the body portion of a fastener is inserted into the groove at one end of one starting tile, and the opposite or projecting end of said fastener fitted into the groove of the adjacent end of the other starting tile, in which manner all of the starting tiles may be mechanically fastened. In uniting the other tiles 10, the abutting ends of which align with the frame rings 9, the body portions of the fasteners are interlocked with the adjacent ends of tiles in like manner, and the hooks 6 of each fastener are engaged with the adjacent frame ring or band, as clearly illustrated in Figs. 2, 3 and 4. The tiles may therefore be readily and conveniently assembled and supported upon the frame rings to close the spaces between said rings and to produce the inner wall or lining, ready for the filling in of the concrete forming the outer wall 11. When this concrete is filled in, it enters the grooves in the tiles and embeds the frame rings and fasteners, and closes any crevices which may exist between the tiles, thereby investing the pedestals, frame rings, tiles and fasteners so that when the concrete hardens a monolithic sewer or conduit having an inner wall of tiles which, may be of an acid proof character, is produced. It will be observed that the connecting members 5 project outwardly through the grooves in the tiles and dispose the hooks 6 at a

definite distance from the body portion of the fasteners, whereby the grooved faces of the tiles are held spaced from the frame rings, allowing the concrete to entirely fill the grooves and embed and interlock all surfaces together. It will be understood, of course, that the hooks 6 have a spring action in gripping the rings or bands 9, which may be of any suitable cross sectional contour, so as to hold the tiles firmly against slipping in the process of assembling said tiles and mounting them on the frame rings.

It will accordingly be observed that my invention provides a fastener which is designed and adapted for a plurality of fastening actions and for holding parts of the character described firmly and securely assembled, and, while I have described the preferred mode of use of the fastener, it will, of course, be apparent that it may be employed for other analogous purposes, and I therefore reserve the right to employ the fastener for any use for which it is adapted.

The fastener employed may be modified to a considerable extent within the scope of the invention. In Fig. 6 I have shown one form of modification which may be employed, the fastener 1^a in this instance being also made of a single piece of wire and of the same general construction as the fastener 1, except that the arms 2 are formed by the ends of the wire, while the cross piece 3' connects the hooks 6 and the arms 4' extend parallel with the arms 2.

Having thus described my invention, what I claim is:—

1. A fastener comprising duplicate parallel members, each consisting of an engaging arm having opposite engaging ends, an extension from one of the engaging ends of the arm projecting toward the other engaging end of the arm, said extension having a portion bent perpendicularly to the plane of the arm and extension, a fastening element carried by said angularly bent portion of the extension, and a connection between said duplicate parallel members.

2. A fastener comprising duplicate parallel members, each consisting of an engaging arm having opposite engaging ends, an extension from one of the engaging ends of the arm projecting inwardly toward the other engaging end of the arm, said extension having its inner end portion bent in a plane perpendicularly to the plane of the arm and extension, a hook carried by the right angularly bent portion of the extension and disposed in a plane parallel with the arm and extension, and a connection between the said duplicate parallel members.

3. A fastener formed of spring wire and comprising substantially parallel engaging arms, portions extending inwardly from one end of said arms and having their end portions bent at right angles thereto, and hooks

upon said right angularly bent portions disposed in spaced relation to the arms.

4. A fastener formed of spring wire and comprising a U-shaped body portion, arms 5 extending inwardly on converging lines from the free ends of the arms of said body portion, extensions arranged at right angles to the free ends of said converging arms, and engaging members carried by said extensions 10 and arranged in spaced relation to the body portion.

5. A fastener formed of spring wire and comprising a U-shaped body portion, arms integral with the free ends of the arms of 15 the body portion and extending inwardly therefrom toward the cross piece of the body portion in converging relation, extensions projecting from the free ends of the converging arms at right angles to the plane of 20 the body portion, and engaging hooks formed upon the free ends of said extensions.

6. The combination with elements to be fastened, one of said elements having a dovetailed groove therein, of a spring wire fastener comprising a U-shaped body portion 25 to interlock with said dove-tailed groove of said member and having hooks arranged in spaced relation to said body portion and 30 adapted to engage the other member.

7. A fastener formed to provide resilient arms connected at one end, other arms integral with the free ends of the resilient arms and disposed between the same, and engag-

ing hooks carried by the free ends of the 35 second named arms.

8. A fastener formed of spring wire formed to provide spaced members having opposite engaging ends, extensions integral with the engaging members at one end, said 40 extensions having portions bent at right angles to said engaging members, and hooks carried by said right angular portions, said hooks being disposed in planes parallel to said members and at a point in the length 45 of the fastener between the engaging ends thereof.

9. The combination with elements to be fastened together, one of said elements having a dovetailed groove therein, of a fastener 50 embodying resilient arms to interlock with said groove of one member, and provided with hooks disposed in spaced relation to said arms to engage the other member.

10. The combination with elements to be fastened together, one of said elements having a dovetailed groove therein, of a spring 55 wire fastener comprising a body formed of spaced resilient arms to interlock with said groove, portions projecting outwardly at 60 right angles to the arms, and hooks carried by said portions to engage the other member.

In testimony whereof I affix my signature in presence of two witnesses.
